INSULATOR SUPPORTING BRACKET FOR
ELECTRIC FENCES

Ernest J. Lenz, Varna, Ill.

Application March 18, 1949, Serial No. 82,119

6 Claims. (Cl. 174—160)

1

This invention relates to a bracket for detachably mounting and supporting an electric insulator in spaced relationship to the plane of a wire fence for providing a means for mounting electric insulators in substantial alignment and so that a charged electric wire may be strung along the aligned insulators and supported thereby to produce an electric fence.

An object of the invention is to mount the supporting bracket or brackets on two barb wires or on the two top or two bottom longitudinal wires of any woven wire fence for protecting fences which are already in use with one or two electric wires as may be needed.

Another object of the invention is to provide a supporting bracket adapted for use in forming a two barbed wire fence and wherein a plurality of the brackets may be employed for mounting a strand of barb wire in offset relationship to the plane of a barbed wire fence.

Another and particularly important object of the present invention is to provide a bracket capable of being quickly attached to or detached from two vertically spaced longitudinally extending strands of a wire fence and so as to project substantially perpendicularly from the plane thereof for supporting a strand of wire in offset relationship to the plane of the fence and to enable the supporting bracket to be mounted at any desired spaced intervals and as near or as far apart as may be necessary or desirable as where the fence line is not straight or where the contour of the land is relatively irregular.

Another important object of the invention is to provide a bracket of the aforescribed character of extremely simple construction which is capable of being economically manufactured and sold, which will be extremely efficient and durable for its intended purpose and which may be quickly and easily applied to or removed from vertically spaced strands of a wire fence.

Numerous other objects and advantages of the invention will hereinafter become more fully apparent from the following description of the drawing, illustrating a presently preferred embodiment thereof, and wherein:

Figure 1 is a side elevational view showing the supporting bracket applied to and detachably supported by vertically spaced strands of a wire fence and supporting an insulator bracket in laterally offset relationship to the plane of said strands;

Figure 2 is a plan view showing the bracket in an extended position, and

Figure 3 is an enlarged cross sectional view of

2

the bracket taken substantially along a plane as indicated by the line 3—3 of Figure 1.

Referring more specifically to the drawing, the supporting bracket comprising the invention is designated generally 5 and is composed entirely of two corresponding strands of wire, designated 6 and 7, which are twisted together throughout a substantial portion of their length and comprising corresponding portions thereof to provide the twisted bracket portions or legs 8 and 9 the adjacent ends of which are spaced from one another by untwisted intermediate portions of the two strands, which intermediate portions are bowed outwardly with respect to one another to define an opening 10 intermediate of the ends of the bracket 5.

Corresponding ends of the strands 6 and 7 which constitute the untwisted extensions of the outer end of the twisted portion or leg 8 are bent 20 to project laterally in opposite directions from the outer end of said leg 8 to provide corresponding arms 11. The terminal of each strand 6 or 7 at the outer end of its arm 11 is turned outwardly to provide a portion 12 which extends 25 in a direction away from the leg 8 and substantially parallel thereto. The portion 12, as seen in Figure 1, is folded downwardly and back upon itself to provide a portion 13 therebeneath which is in turn folded downwardly and back upon itself to provide a bottom portion 14 which is spaced downwardly from the portion 13 to provide an outwardly opening notch or recess 15. The portion 14 which constitutes the terminal of its arm portion 11 extends outwardly to substantially 30 beyond the portions 12 and 13 and as clearly illustrated in Figure 1, said portions 12, 13 and 14 of each arm 11 constitute three substantially superimposed folds or plies of an end of either the strand 6 or 7.

40 The opposite ends of the strands 6 and 7, at the outer end of the leg 9 constitute separate terminal portions which project from said leg 9 substantially at right angles thereto and in opposite directions to form the arms 16 having outwardly 45 turned portions 17 at their outer ends which project in directions away from the leg 9 and which are disposed substantially parallel thereto and which are turned inwardly and back upon themselves to form the inwardly opening hooks 18 which are disposed on the opposite side of the plane of the supporting bracket to the folds 13 and 14.

The legs 8 and 9 are bent adjacent the bracket opening 10 to form the bracket 5 of substantially 55 V-shaped formation and with the opening 10 con-

stituting the apex thereof. A conventional electrical insulator 19 is adapted to be disposed with one end thereof against the outer side of said apex portion of the bracket 5 and the shank of the bolt 20 which extends longitudinally through the insulator 19 extends inwardly through the opening 10 and has a nut 21 applied to its threaded end and which bears against the inner side of said apex portion and demountably fastens the insulator 19 to the bracket 5, as clearly illustrated in Figure 1.

The bracket 5 is adapted to be disposed with its axis in substantially a horizontal plane, as illustrated in Figure 1, with the leg 9 constituting the upper leg thereof and the leg 8 the lower leg of the bracket. When so disposed, the hooks 18 are positioned substantially directly above the portions 12, 13 and 14 and with the hooks 18 opening downwardly and inwardly of the bracket 5 and the notches 15 opening downwardly and outwardly thereof. The hooks 18 are engaged over one longitudinally extending strand 23 of a wire fence after which the bracket 5 is swung downwardly in a clockwise direction to its position of Figure 1 to cause another, lower longitudinally extending strand 23a of the wire fence to be engaged in the notches 15 to thereby detachably mount the bracket 5 on the strands 23 and 23a and so that said bracket will project outwardly from one side of the fence substantially perpendicular to the plane thereof. It will thus be readily seen that the insulator 19 will be supported at a distance from the fence strands 23 and 23a and said insulator is provided with a groove 24 for receiving a portion of a strand of wire 25 which is intended to be electrically charged and which is adapted to be supported by a plurality of insulators 19 each supported by a bracket 5 on the strands 23 and 23a and which additional brackets, not shown, are spaced longitudinally along said strands 23 and 23a at any desired distances depending upon the contour of the land along which the fence strands extend and also depending upon whether or not the fence is straight or crooked. Obviously, if desired, the strand 25 could be wrapped or looped around the groove 24 or may be supported, as illustrated, by merely resting in the upper portion of said groove. The bracket 5 may be made of various sizes but is preferably of a size to permit the wire 25 to be supported approximately six inches from the plane of the fence strands 23 and 23a. It will also be readily apparent that the bracket 5 may be adjusted to accommodate it to fence strands spaced various distances apart by bending the legs 8 and 9 toward or away from one another. The bracket 5 may obviously be placed either adjacent the top or adjacent the bottom of a wire fence to keep cattle from reaching over the fence or to prevent hogs from going under the fence. It will also be readily apparent that the fence strands 23 and 23a will ordinarily constitute horizontal or longitudinal strands of a woven wire fence; and that a plurality of the brackets 5 may be utilized for supporting a strand of barb wire in lieu of the electrically charged wire 25 and in offset relationship to the vertical plane of a fence.

Various other modifications and changes are likewise contemplated and may obviously be resorted to, without departing from the spirit or scope of the invention as hereinafter defined by the appended claims.

I claim as my invention:

1. A readily demountable supporting bracket 75 for use with wire fences comprising a substan-

tially V-shaped bracket including an upper leg and a lower leg, said upper leg being provided with laterally spaced inwardly opening hooks adapted to engage one longitudinally extending strand of a wire fence, the other, lower leg of said bracket being provided with laterally spaced outwardly opening notches normally disposed to open downwardly and being adapted to engage another, lower longitudinally extending strand of the wire fence for supporting said bracket in outwardly projecting relationship to the plane of said strands, and means at the apex of the bracket for detachably supporting a strand of wire thereon and in offset relationship to the fence strands.

2. A supporting bracket as in claim 1, said bracket being formed of two strands of wire having complementary twisted portions defining said legs, complementary end portions of the strands, beyond the outer end of said upper leg, each forming one of said inwardly opening hooks, constituting the hooks for engaging the first mentioned fence strand, said hooks being laterally offset from the axis of said upper leg and in opposite directions, the opposite, complementary ends of the bracket strands beyond the outer end of the lower leg being bent to provide the corresponding outwardly opening notches for engagement with said lower fence strand, said outwardly opening notches being laterally offset from the lower bracket leg and in opposite directions.

3. A supporting bracket as in claim 1, said bracket being formed of two strands of wire having complementary twisted portions defining said legs, complementary end portions of the strands, beyond the outer end of said upper leg, each forming one of the inwardly opening hooks, constituting the hooks for engaging the first mentioned fence strand, said hooks being laterally offset from the axis of said upper leg and in opposite directions, the opposite, complementary ends of the bracket strands beyond the outer end of the lower leg being bent to provide the corresponding outwardly opening notches for engagement with said lower fence strand, said outwardly opening notches being laterally offset from the lower bracket leg and in opposite directions, and said bracket strands having untwisted intermediate portions forming an opening in the apex of the bracket adapted to receive an insulator fastening constituting a part of the means for supporting a strand of wire on the bracket.

4. A supporting bracket as in claim 1, said legs being bendable toward and away from one another for mounting the bracket on fence wire strands spaced different distances apart.

5. A supporting bracket for wire fences formed of two strands of wire having complementary twisted portions forming legs, said legs being disposed at an acute angle to one another, one of said legs constituting the upper leg of the bracket and complementary ends of the strands of wire beyond the outer end of said upper leg being bent to define corresponding inwardly opening hooks which are laterally offset in opposite directions from the axis of said upper leg and adapted to engage one longitudinally extending strand of a wire fence, the opposite, complementary ends of the bracket strands, beyond the outer end of the other, lower bracket leg being bent to define outwardly opening corresponding notches which are laterally offset in opposite directions from the axis of said lower leg and adapted to engage another, lower longitudinally extending fence strand for supporting said bracket detachably on said fence strands and in outwardly projecting rela-

tionship from one side of the plane thereof, and means at the apex of said legs for demountably supporting another strand of wire in laterally offset relationship to the fence wire strands.

6. A supporting bracket as in claim 5, said means including an electrical insulator having a mounting fastening projecting from one end thereof and said bracket strands having un-twisted complementary intermediate portions defining an opening at the apex of said bracket legs for detachably receiving the insulator fastening for detachably mounting the insulator on the outer side of the apex of the bracket, said insulator being adapted to demountably support the last mentioned strand of wire.
